ELECTRON GUN FOR BEAM-TYPE TUBES

Donald H. Preist, Mill Valley, Calif., assignor to Eitel-McCullough, Inc., San Bruno, Calif., a corporation of California

Application October 5, 1953, Serial No. 384,097

9 Claims. (Cl. 315—3)

My invention relates to an improved electron gun structure for beam-type tubes such as klystrons, traveling wave tubes, and the like.

The principal object of my invention is to provide a simple gun structure for producing a high permeance electron beam.

Another object is to provide an electron gun wherein the permeance of the beam may be varied externally of the tube.

Another object is to provide a gun structure which protects the cathode from positive ion bombardment.

A further object is to provide an electron gun which enables the beam to be modulated in an improved manner.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

The single figure is a vertical sectional view, partly diagrammatic, showing a beam-type tube embodying the improvements of my invention.

It is often advantageous in klystrons, traveling wave tubes and similar beam-type devices to use a high permeance beam, namely, a beam in which the ratio of the current is the beam to the electron velocity is as high as possible. With electron guns constructed in accordance with conventional practice where the electrons are accelerated by a positive potential on the anode with respect to the cathode, the highest value of permeance obtainable is generally considered to be about 10×10^{-6} (amperes per volt^{3/2}). Expressed in microamperes this is called a permeance 10 gun. Such high permeances are very difficult to attain because of beam focusing problems and the very close tolerances required on the dimensions of the gun structure. As a result, tubes in actual practice have relatively low permeance guns, say of the order of 1×10^{-6} (amperes per volt^{3/2}). Such permeance 1 guns are not too difficult to make on a quantity production basis and for that reason are frequently used in commercial tubes, even though higher permeance beams would be desired.

With my improvements the permeance of an electron gun may be increased manyfold without difficulty. As shown in the drawing, the structure comprises a disk-shaped cathode 2 supported by a stem 3 and heated by a suitable filament or heater 4. The electrons from the cathode are focused into a circular beam 6 through an apertured anode 7 by a suitable tubular focusing electrode 8, the anode 7 being operated at a positive potential with respect to the cathode as indicated by the D. C. voltage source V_A connected between the anode and cathode. An insulating cylinder 9 supports the cathode structure in vacuum tight relationship with respect to the

2

anode. The above described construction is conventional practice, the details of such electron gun design being well understood by those skilled in the art. As previously mentioned, it is not too difficult to produce a beam having a permeance value of unity with guns of this general type.

In my improved construction additional means are provided as a part of the gun structure and ahead of the anode 7 for decelerating the electrons after they emerge from the anode. Such means preferably comprises a decelerating electrode 11 spaced from the anode 7 by an insulating cylinder 12 which also forms part of the evacuated envelope of the tube. Electrode 11 is apertured to receive the beam 6 and preferably has a tubular projection 13 opposite a similar projection 14 on the anode 7 to provide a gap 16. Electrode 11 is also operated at a positive potential with respect to the cathode as indicated by the D. C. voltage source V_B , but the decelerating electrode voltage V_B is made less than the anode 20 voltage V_A so that the electrons are decelerated as they pass through gap 16.

The beam emerging from the decelerating electrode 11 of my improved gun structure then passes into a main radio frequency section of the tube indicated by the dotted line 17, which latter section may be a klystron type of device having resonant cavities or a traveling wave tube or any other similar beam-type of device adapted for interaction with the beam.

The principle of operation of my improved electron gun is as follows:

First considering the initial gun formed by the cathode 2 and anode 7, if I is the beam current and K is the permeance of such cathode-anode structure in microamperes per volt^{3/2}, the following relationship exists:

$$I = K \times V_A^{3/2}$$

Now considering the addition of the decelerating device it is seen that with a properly focused beam the current I of the beam emerging from the electrode 11 is the same as that issuing from the anode 7, but the velocity of the electrons in the emerging beam will be reduced by reason of the lower voltage V_B on the decelerating electrode 11. This is expressed as:

$$I = K \left[\frac{V_A}{V_B} \right]^{3/2}$$

or as

$$I = K \left[\frac{V_A}{V_B} \right]^{3/2} \times V_B^{3/2}$$

from which the effective permeance of the combination of the initial gun and the decelerating device is given

$$\frac{I}{V_B^{3/2}} = K \left[\frac{V_A}{V_B} \right]^{3/2}$$

In other words, the effective permeance of the final combination is a function of the voltage ratio

$$\frac{V_A}{V_B}$$

For example, if

$$\frac{V_A}{V_B} = 5$$

and $K=1$, the effective permeance of my improved gun structure will be $1 \times 5^{3/2} = 11.15$. Theoretically there appears to be no reason why the ratio

$$\frac{V_A}{V_B}$$

70 should not be increased indefinitely.

Thus I have provided a simple means for producing

high permeance beams with an initial low permeance cathode-anode structure which is relatively easy to manufacture in mass production operations. In addition to increasing beam permeance, my improved gun structure has further advantages.

Heretofore beam permeance has been a fixed parameter set by the geometry of the gun. With my improved electron gun having a decelerating electrode, the beam permeance may be controlled or changed externally of the tube by adjusting the voltage ratio

$$\frac{V_A}{V_B}$$

Also because the anode 7 may be operated at a potential more positive than the electrodes 2 and 11, any positive ions in the tube structure ahead of the gap 6 will not be attracted back toward the cathode 2. The cathode is thus protected against positive ion bombardment which is frequently destructive in beam-type tubes, particularly when oxide-coated cathodes are used in conjunction with high accelerating fields.

Another advantage is that it is possible to modulate the beam current 100% by varying the voltage V_A while leaving the voltage V_B fixed. This is particularly adapted for modulation by very fast wave forms such as short pulses and enables low power modulators to be used for modulating relatively high power beams.

It is thus seen that my improved construction has important advantages other than that of increasing the beam permeance. In any case the advantages came about because of the particular combination of elements making up the gun structure, namely, a pair of spaced electrodes 7 and 11 having apertures coaxially aligned with the cathode 2 and disposed between the latter and the main section 17 of the tube, together with means such as the focusing device 8 for focusing the beam 6 of electrons through the apertures of the spaced electrodes 7 and 11, which electrodes are provided with terminals externally of the tube envelope.

I claim:

1. A beam-type tube having a radio frequency section and a controllable permeance gun structure comprising a cathode for initiating an electron beam, and an apertured anode having a tubular projection thereon and positioned intermediate said cathode and said radio frequency section, said anode being adapted to operate at a certain D. C. potential with respect to said cathode to produce a certain beam permeance and means included in said gun structure for controlling said permeance including an apertured electrode intermediate said anode and said radio frequency section and having a tubular projection extending in the direction of the tubular projection on said anode, said last-mentioned means further including means for operating said electrode at a D. C. potential lower than said certain D. C. potential to increase said beam permeance.

2. In an electron tube of the beam type having a main radio frequency section, an electron gun comprising cathode means for emitting a beam of electrons, anode means intermediate said cathode means and said section for accelerating the electrons and means including an electrode intermediate said anode means and said section for increasing the effective permeance of said tube, said last-mentioned means including means for controlling said beam of electrons in accordance with the formula:

$$\frac{I}{V_B^{3/2}} = K \left[\frac{V_A}{V_F} \right]^{3/2}$$

where I is the beam current in microampères, V_A is the anode voltage in volts, V_B is the electrode voltage in volts, and K is the permeance of said cathode-anode structure in micrcampères per volt^{3/2}.

3. In a beam type tube having a radio frequency section, an electron gun for directing a variable permeance beam of electrons through said section comprising a

cathode, a first insulating cylinder connected to said cathode, an apertured anode abutting said cylinder and axially aligned with said cathode, a second insulating cylinder connected to said anode and an apertured electrode abutting said second cylinder and having a tubular portion extending toward said anode, said electrode being axially aligned with said anode.

4. An electron gun in accordance with claim 3 wherein said anode has a tubular portion extending toward the tubular portion of said electrode.

5. A variable permeance electron gun for developing a stream of electrons in a velocity modulated tube, said gun comprising a cathode having a concave emissive surface, a focusing electrode adjacent said cathode, a first anode mounted in front of said concave emissive surface of said cathode and insulated therefrom, said first anode having an aperture therethrough coaxial with said emissive surface of said cathode, and a second anode mounted on the opposite side of said first anode from said cathode, said second anode being insulated from said first anode and said cathode and having an aperture therethrough coaxial with the aperture through said first anode, said first anode electrostatically shielding said cathode and said focusing electrode from said second anode.

25 6. A variable permeance electron gun for developing a stream of electrons in a velocity modulated tube, said gun comprising a cathode disk having a concave emissive surface, a tubular focusing electrode surrounding said cathode disk, a first insulating cylinder coaxial with said cathode and said focusing electrode, said cathode and said focusing electrode being suitably mounted on a stem member which is hermetically sealed to and closes one end of said first insulating cylinder, said first anode disk having an aperture therein coaxial with said cathode and said focusing electrode, a second insulating cylinder coaxial with said anode disk aperture, one end of said second insulating cylinder being hermetically sealed to the opposite side of said first anode disk from said first insulating cylinder, and a second anode disk hermetically sealed to the other end of said second insulating cylinder, said second anode disk having an aperture therethrough coaxial with the aperture in said first anode disk.

7. A variable permeance electron gun for a velocity modulated tube, said gun comprising a cathode disk having a concave emissive surface, a tubular focusing electrode coaxially surrounding said cathode disk, a first insulating cylinder coaxial with and surrounding said cathode and said focusing electrode, said cathode and said focusing electrode being suitably mounted on a stem member which is hermetically sealed across one end of said insulating cylinder, a first anode disk hermetically sealed across said other end of said first insulating cylinder, said first anode disk having an aperture therein coaxial with said emissive surface of said cathode and said focus electrode, said first anode disk having an annular projection on the opposite side thereof from said cathode and surrounding said aperture whereby a passage way is provided having a length greater than its diameter, a second insulating cylinder coaxial with said aperture in said first anode disk, one end of said second insulating cylinder being hermetically sealed to the opposite side of said first anode disk from said first insulating cylinder, and a second anode disk hermetically sealed to the other end of said second insulating cylinder, said second anode disk having an aperture therethrough coaxially aligned with the aperture and passageway of the said first anode disk.

8. An electron gun for a velocity modulated tube, said gun comprising a cathode disk having a concave emissive surface, a tubular focusing electrode surrounding said cathode disk, a first ceramic insulating cylinder coaxial with and surrounding said cathode and said focusing electrode, said cathode and said focusing electrode being mounted on a stem member which is hermetically sealed to one end of said first insulating cylinder, a first anode disk hermetically sealed across the other end of said in-

sulating cylinder, said first anode disk having an aperture therein coaxial with said emissive surface of said cathode, means including a voltage source for operating said first anode disk at a given d. c. potential with respect to said cathode to produce a given beam current, said emissive surface of said cathode, said focusing electrode, said first anode disk, and the aperture through said first anode disk being dimensioned and spaced from each other so that the diameter of the electron beam at said first anode disk is less than the diameter of said aperture in said first anode disk at said given current and potential, an annular projection on the opposite side of said first anode disk from said cathode and surrounding said aperture whereby a passageway is provided having a length greater than the diameter thereof, a second ceramic insulating cylinder coaxial with said aperture in said first anode disk, one end of said second insulating cylinder being hermetically sealed to the opposite side of said first anode disk from said first insulating cylinder, a second anode disk hermetically sealed to the other end of said second insulating cylinder, said second anode disk having an aperture coaxially aligned with the aperture and passageway of said first anode disk, and means including a voltage source for operating said second anode disk at a different potential from said first anode disk, said second anode disk being spaced from said first anode disk and said anode disk aperture in said second anode disk being dimensioned such that the diameter of said electron beam at said second anode disk is less than the diameter of said aperture in said first anode disk.

9. A velocity modulated electron tube including an electron gun, said gun comprising a cathode disk having a concave emissive surface, a tubular focusing electrode surrounding said cathode disk, said cathode and said focusing electrode being suitably mounted on a stem member, a first insulating cylinder coaxial with and surrounding said cathode and said focusing electrode, one end of said insulating cylinder being hermetically sealed to said

stem member, the other end of said first insulating cylinder projecting beyond the end of said focusing electrode, a first anode disk hermetically sealed to the other end of said insulating cylinder, said first anode disk having an aperture therein coaxial with said cathode and said focusing electrode, means including a voltage source for operating said first anode disk at a given positive potential with respect to said cathode to produce a given beam current, said emissive surface of said cathode, said focusing electrode, said first anode disk, and said aperture in said first anode disk being dimensioned and spaced such that the electron beam produced thereby has a certain desired perveance, an annular projection on the opposite side of said first anode disk from said cathode and surrounding said aperture whereby a passageway is provided having a length greater than the diameter thereof, a second insulating cylinder coaxial with said cathode, focusing electrode and aperture in said first anode disk, one end of said second insulating cylinder being hermetically sealed to the opposite side of said first anode disk from said first insulating cylinder, a second anode disk hermetically sealed to the other end of said second insulating cylinder, said second anode disk having an aperture therethrough coaxially aligned with the aperture and passageway of said first anode disk, and means including a voltage source for operating said second anode disk at a lower positive potential with respect to said first anode disk than said given potential to increase said certain perveance.
